CLAIM

The ornamental design for a pump for circulating coolant in electronic devices, as shown and described.

DESCRIPTION

FIG. 1 is a top perspective view of a pump for circulating coolant in electronic devices of the present invention; FIG. 2 is a front view thereof; FIG. 3 is a rear view thereof; FIG. 4 is a first side view thereof; FIG. 5 is a second side view thereof; FIG. 6 is a top view thereof; and, FIG. 7 is a bottom view thereof.
